WILLIAM W. SPALDING, OF GREENLAND, MICHIGAN

Letters Patent No. 65,703, dated June 11, 1867.

IMPROVED JIGGING MACHINE FOR DRESSING ORES.

The Schedule referred to in these Letters Patent and making part of the same.

TO ALL WHOM IT MAY CONCERN:

Be it known that I, WILLIAM W. SPALDING, of Greenland, in the county of Ontonagon, and State of Michigan, have invented a new and useful improvement in Jigging Machines; and I do hereby declare that the following is a full, clear, and exact description thereof, which will enable others skilled in the art to make and use the same, reference being had to the accompanying drawings, forming part of this specification, in which—

Figure 1 is a vertical section of my improved jigging machine, taken in the plane of the line $x\ x$, fig. 2.

Figure 2 is a plan or top view.

Figure 3 is an enlarged sectional view of a detail cut in the plane of the line $y\ y$, fig. 4.

Figure 4 is a sectional view of the same part cut in the plane of the line $z\ z$, fig. 2.

Figure 5 is a sectional view of the ragging-box, cut in the plane of the line $w\ w$, fig. 1.

Similar letters of reference indicate like parts.

This invention relates to improvements in jigging machines, and consists in novel arrangements and devices for washing the ores of copper, lead, silver, and other metals after they have been pulverized in a stamp-mill, and separating the minerals or metals from the rock and earthy substances associated with them in the ore. The machinery in general use for jigging ores is more or less expensive, and complicated in construction, and imperfect in operation. My improved jigging machine is simple, cheap, and efficient; the crushed ores are rapidly and thoroughly washed, and the minerals or metals separated clean from the rock and earthy parts of the ore. This machine may be applied to ores of all descriptions.

The drawings represent a double machine, that is to say, two machines together, any number of which may be placed side by side in the same manner, each separate machine being constructed and operated alike. The following description, therefore, applies to only one machine or part having a distinct and independent operation.

A represents a water-box for washing or jigging the pulverized ores. The ground plan of the main compartment is rectangular and nearly square, as shown by fig. 2. The top and bottom are level, and the front side is made sloping back from the top to the bottom. At the upper part of the back of the main box is a plunger-box, B, communicating with it by a wide opening or throat, a , and on the top is a wire sieve, b, placed several inches below the upper edge of the box. The floor c of the plunger-box B inclines forward, and is extended to form an inclined false bottom, c' , in the main box A, in which is a narrow opening or throat, d , that runs across the box to form a separate compartment, A', in the back part, into which the water for washing the ores is conveyed by a pipe indicated in red from a source above the level of the machine to keep it always full of water, as shown in fig. 1. The main compartment of the box A is provided with a discharge pipe, e, at the bottom in front, and the smaller compartment A' with a discharge pipe, e', at the back. A plunger, C, is pivoted or hinged on one side to the front part of the plunger-box B level with the top of the main box box A, and is suspended at the back part by an adjustable bail or bow, g, which straddles an inclined apron, D, that sets above the box B. The bail g is hung to a crank-shaft, h, running in the caps a^2 of the frame-posts $a^1\ a^1$, by which the plunger C is operated. A rake, k, is placed on the sieve b, and receives a sliding motion forward and back by means of a counter-shaft, l, with which it has a crank connection, and that is turned by a band, m, running from the shaft h over pulleys m^1, m^2 . The pulverized ore is conveyed to the apron D in the ordinary way, and passes thence on to the sieve b, where the rake k agitates and loosens the mass and cuts the slime in its passage over the sieve, while at the same time the plunger D, which is lifted by the rotation of the crank-shaft h, rises and falls suddenly in the plunger-box B, and thus produces a pulsating movement in the water in the box, forcing it up through the sieve intermittently, and suspending the lighter portions or earthy waste matters which are carried forward by the current of water to the tail of the machine, while the heavier or metallic portions either settle on the bottom of the sieve or pass through it into the box. The coarser parts of the mineral that will not pass through the sieve are allowed to accumulate to a certain depth on the sieves, and form what is called the ragging or bottom, which, by its density, aids in supporting and carrying off the refuse or waste sands. In my machine the ragging is kept at the required depth by its own operation, the surplus being discharged by means of a self-regulating device placed at the tail of the machine, which allows it to pass into a ragging-box in front.

E is a closed ragging-box attached to the front side or tail end of the main box A. The ragging-box E

is a flat, three-cornered box set on the front side of the main box A, with one of its sides level with the top thereof, and one of its corners pointing downwards, as shown in fig. 5. At the bottom of the ragging-box is a discharge pipe, n, fig. 5, and at the top is a narrow slot, n', opening into a guard, F, placed just inside of the upper edge of main box A, and having its lower edge slightly raised above the sieve b to allow the passage of the coarser mineral under it to a self-acting gate, p, that leads to the opening n' in the ragging-box. The guard F is open above and below, and is triangular in shape, one corner pointing towards the rake k to act as a guard and guide for carrying off the waste, and allowing only the heavy mineral to pass under it to the ragging-box. The gate p is hung with a counterbalance weight and lever, q, attached, which keep it closed until the resistance of the counterpoise is overcome by the accumulated pressure of the mineral, when it opens and the mineral passes into the ragging-box. This automatic operation of the gate is constantly repeated, and thus the ragging-bed on the sieve is self-regulated at the required depth. The coarse mineral is drawn off from the ragging-box through the discharge pipe n. The gate p is shown open in fig. 4.

The heavy and finer metallic portions of the pulverized ore pass through the head of the sieve b and fall on the upper part of the floor c', and run down until they meet the current of water rising up from the supply-box A' through the passage or throat d, which cleanses the mineral of any refuse sands so that it falls through the opening d into the box A', and issues through the discharge pipe e' at the back of the machine in a highly purified condition. The lighter portion is carried forward in the main box and finds exit through the discharge pipe e in front.

The whole combined operation of the several parts that have been described in their construction and operation separately will be readily understood.

Having thus described my invention, what I claim as new, and desire to secure by Letters Patent, is—

1. I claim the main box A in combination with the plunger-box B, having a water-passage or throat, a, connecting them, and divided into two compartments, with the water-passage d between them, and discharge pipes e e' leading from them, arranged and operating substantially as and for the purposes herein described.
2. The plunger C, pivoted or hinged at one side, in combination with the box B, the main box A, and the sieve b, arranged and operating substantially as and for the purposes specified.
3. The combination of the closed ragging-box E attached to the front side of the main box A, the self-regulating gate p, and the guard F, constructed, arranged, and operating substantially as and for the purposes set forth.
4. The rake k, in combination with the counter-shaft l, the crank-shaft h, and the sieve b, arranged and operating as and for the purpose described.
5. The combination and arrangement of the main box A, the plunger-box B, the plunger C, the bail g, the apron D, the rake k, the guard F, the gate p, and the ragging-box E, substantially as and for the purposes herein described.

WILLIAM W. SPAULDING.
